Primary Examiner — Darlington Ly*Assistant Examiner* — Nasim Abdulaziz Ali(74) *Attorney, Agent, or Firm* — Robert C. Netter, Jr.; Dann, Dorfman, Herrell & Skillman(57) **CLAIM**

We claim the ornamental design for an electric three-wheeled vehicle, as shown and described.

DESCRIPTION

FIG. 1 is a left side elevation view of an electric three-wheeled vehicle showing my new design;

FIG. 2 is a right side elevation thereof;

FIG. 3 is a front elevation view thereof;

FIG. 4 is a rear elevation view thereof;

FIG. 5 is a top plan view thereof;

FIG. 6 is a bottom plan view thereof; and,

FIG. 7 is a front perspective view thereof.
